(57) **CLAIM**

The ornamental design for a spinning target element, as shown.

DESCRIPTION

FIG. 1 is a perspective view of the top side of a spinning target element.

FIG. 2 is a front elevation view of the spinning target element, the back elevation view being the same as the front elevation view.

FIG. 3 is a right side elevation view of the spinning target element, the left side elevation view being the same as the right side elevation view.

FIG. 4 is a top plan view of the spinning target element; and, FIG. 5 is a bottom plan view of the spinning target element.
